Saml. D. Vose, of Albany, N. Y.
Letters Patent No. 576. Dated June 28th 1853,
Ante-dated May 2^d. 1853,

.....

The schedule referred to in these Letters Patent and making part of the same
.....

To all whom it may concern:

Be it known that I, Saml. D. Vose, of the City and
County of Albany and State of New York have invented or produced a new design for
a Parlor Stove (E) and I do hereby declare that the following is a full & exact descrip-
tion of the same reference being had to the drawings annexed and making part of this
specification.

The invention not being easily described in words, reference is
made to the drawings.

In the drawings the letter U refers to the urn of the stove.

I	"	"	upper top	"	"	"
t.	"	"	lower top	"	"	"
f.	"	"	upper front	"	"	"
F	"	"	lower front	"	"	"
H	"	"	hearth	"	"	"
E	"	"	lower end	"	"	"
e	"	"	upper end	"	"	"

I. " " " legs " " "
B. " " " back " " "

My invention has no reference to any single moulding or ornaments on said plates, but consists in the configuration & disposition of the ornaments in connection with the mouldings.

I claim no separate configuration or part

What I claim as my invention & desire to secure by letters patent of the United States is the combination of mouldings & ornaments as arranged on the parlor stove (E) the whole forming an ornamental design.
